PACKAGE

Paul J. Johnson, Watertown, Conn., assignor to
Scovill Manufacturing Company, Waterbury,
Conn., a corporation of Connecticut

Application May 12, 1932, Serial No. 610,798

2 Claims. (Cl. 206—66)

This invention relates to packages or containers and more particularly to fillers such as are usually associated with containers of different types for holding the contents in prearranged condition.

In packing such articles, for example, as pins, nails, clips, or the like it is customary to reciprocate the container as the articles are fed into it. Such reciprocation causes the articles to arrange themselves longitudinally of the container in generally well defined rows. It will be apparent that a given weight of articles of one size will take up more space than the same weight of articles of another size, and heretofore, it has frequently been necessary to provide containers in a comparatively large range of sizes to properly package articles such, for example, as pins of different sizes.

An object of this invention is to provide a package of articles of the type set forth constructed and arranged to permit a single size of container being used to package articles of different sizes.

A further object is to provide a filler for containers constructed and arranged to hold articles in a prearranged condition irrespective of variations in the amount of space assumed by articles of different sizes or by different articles.

These and other objects which will be apparent to those skilled in this particular art are accomplished by means of the invention illustrated in the accompanying drawing in which,

Fig. 1 is a perspective view of a package of pins constructed in accordance with one embodiment of this invention, the several parts of the package being separated for better illustration, and

Fig. 2 is a sectional view of the package shown in Fig. 1, the parts being assembled in operative relation.

Although the following description refers particularly to pins, it will be apparent that the invention is equally applicable to other articles of the same general type.

As illustrated in the drawing, the invention comprises a container 5 of conventional form into which the pins 6 are fed in the usual manner from a pin-making machine or from any other source. In accordance with established practice, while the pins are being fed into the container 50 the latter is reciprocated longitudinally for the purpose of causing the pins to arrange themselves longitudinally in the container. By reciprocating the container at such a rate as approximately 200 reciprocations per minute, the pins will be thereby positioned in two, three or more piles,

depending upon the dimensions of the container and the length of the pins in relation thereto. The container is filled with pins only to a level below the plane of its upper edge so that the reciprocating operation will not cause any of the 60 pins to be spilled.

In order to permit a single container to be used for tightly packing pins of any size, and for holding the pins in their arranged and grouped positions in the container, regardless of 65 variations in the amount of space which pins of different sizes require, I position a filler 7 in the container above the pins, which is adapted to be pressed into engagement with the pins to hold them in their arranged positions. The filler has 70 a body portion 8 which is transversely yieldable and the edges of the filler are turned upwardly to form upwardly extending flanges 9 which are engaged by the cover 10 when the latter is in place so as to press the filler downwardly into 75 holding engagement with the pins 6 or other articles. The flanges 9 are so formed that the filler will be pressed into holding engagement with the pins irrespective of variations in the level of such pins in the container. Variations 80 in the amount of space which the pins occupy are accommodated by the transversely yieldable body portion of the filler. When more space is taken by pins of one lot than those of another, the body portion of the filler will yield transversely as it is pressed into holding engagement therewith, so as to compensate for the greater amount of space required by the pins. This is illustrated on a somewhat exaggerated scale in Fig. 2. If less space is taken by the articles the 85 body portion 8 will flatten out and still hold the pins as desired.

It will be apparent that the edges of the filler will occupy substantially the same position in the container regardless of the size of articles 90 packaged, such position being determined by the dimensions of the upturned flanges 9, the variations in space required for the contents being accommodated by the flexible body portion 8.

The filler 7 may have advertising information 100 or the like printed on its face, and it may also be used as a display tray merely by removing the cover 10.

I claim:—

1. An article of manufacture comprising a container, a cover, contents of variable volume filling said container to a level below the plane of its upper edge, a contents engaging filler positioned in said container above and in contact with said contents, upwardly extending edges 110

formed on said filler and engaging the inner face of said cover when closed to press the edges of said filler downwardly into engagement with said contents, said filler having a flexible body portion adapted to yield upwardly when the edges of said filler are pressed against said contents, to accommodate and hold variable quantities of said contents in said container.

5 2. A pin package comprising a container, a cover, a quantity of pins filling said container to a level below the plane of its upper edge, a pin

holding filler having a transversely yieldable body portion engaging the upper surface of said pins, upturned edges formed on said filler and positioned to engage the inner face of said cover when closed whereby when said edges are pressed downwardly into engagement with said pins said body portion will yield transversely to accommodate and hold variable quantities thereof in said container.
